UNITED STATES PATENT OFFICE.

EDWIN T. BRIGHAM, OF KANSAS CITY, MISSOURI, ASSIGNOR TO JACQUES ROUSSO, OF LOS ANGELES, CALIFORNIA.

TOWEL-RACK.

1,378,214.

Specification of Letters Patent. Patented May 17, 1921.

Application filed September 26, 1912. Serial No. 722,473.

To all whom it may concern:

Be it known that I, EDWIN T. BRIGHAM, a citizen of the United States, residing at Kansas City, in the county of Jackson and 5 State of Missouri, have invented certain new and useful Improvements in Towel-Racks, of which the following is a specification.

This invention relates to towel racks for use chiefly in public buildings, hotels, bath 10 houses and the like, where it is a frequent occurrence for hand or face towels to be carried away or thrown carelessly aside, and my object is to produce a simple and efficient rack designed chiefly for the support 15 of towels of the class mentioned, whereby the towels are accessibly supported with more than a reasonable degree of security against loss, and upon which towels as used, can be isolated from the unused or 20 clean ones.

With this general object in view, the invention consists in certain novel and peculiar features of construction and organization as hereinafter described and claimed; 25 and in order that it may be fully understood reference is to be had to the accompanying drawing, in which—

Figure 1, is a side elevation of a towel rack embodying my invention.

Fig. 2, is a full-sized vertical section of 30 the upper bracket of the rack, and also shows the upper extremity of the rod of the rack, in engagement with the said bracket.

Fig. 3, is a similar section of the lower bracket and also shows the lower extremity of the rod engaging said bracket and a device for preventing disengagement of said parts.

Fig. 4, is a face view of the lower bracket.

In the said drawing, a bracket 1, consists of a hollow vertically-elongated socket portion 2, provided at its upper corner with an opening 3, lying in an inclined plane, and a 45 flange 4, projecting outwardly from the socket portion, and secured to a suitable support by screws 5, or equivalent attaching devices.

Vertically below the bracket described, is 50 a second bracket 6, consisting of a hollow vertically-elongated socket portion 7, and a flange 8, through which attaching devices 9 extend to fasten it to the support. In the front or inner end of the socket portion is 55 formed an inverted keyhole slot 10, and in

one of the side walls of said socket portion is an opening 11, for a purpose which hereinafter appears.

A spring rod 12, of U-shape is arranged so as to form an upright portion and two 60 substantially horizontal arms, the upper arm being arched or humped at 12^a where it projects from the upright portion, for a purpose which hereinafter appears.

The upper arm is also bent downward at 65 13 and terminates at its free end in a short horizontal portion 14, the construction being such that an upper and a lower shoulder 15 and 16 respectively, are formed at the junction of portions 13 and 14, the shoulder 15 being disposed nearer the free extremity of portion 14 than the shoulder 16, so that when the portion 14 is fitted in the socket portion 2, shoulder 15 will bear against the upper portion of the wall of the inclined 75 slot 3, and the shoulder 16, which faces in the opposite direction from shoulder 15, will bear against the lower portion of the wall of said opening, as shown clearly in Fig. 2.

To fit the upper arm of the rod in socket 80 portion 2, the said arms must be arranged at such an angle that it shall extend approximately at right angles to the inclination of the opening 3. It is then slipped into said opening until the shoulder 15 engages the upper part of the wall of said opening, by which time the shoulder 16 is approximately in the plane of the inclination of the opening. The rod is then swung 85 downward until its portion 14 bears against the overlying part of socket portion 2, and shoulder 16 is within said socket portion and adjacent to the lower wall of its opening 3. When thus arranged it will be impossible to withdraw the upper end of the rod from 90 opening 3, without first swinging the rod upwardly to substantially the position it occupied when inserted in the socket.

Formed in opposite sides of the rod, adjacent to its other extremity, are notches 100 17, adapted to be engaged by the vertical side walls of the narrow portion of the key-hole slot. Before such engagement can take place however, the rod must be sprung downward to permit its lower end to be 105 pushed into the enlarged end of said key-hole slot, and as this occurs, the tendency of the rod to retract to normal condition, causes said end to spring upward and its notches to receive the said side walls of the 110

narrow portion of the slot, the engagement of said walls with said notches preventing disengagement of the lower arm of the rod from the lower bracket until the rod is 5 again sprung downward sufficiently to cause its lower end to enter the enlarged portion of said slot.

To prevent an unauthorized person from accomplishing the purpose last referred to, 10 the hasp of a small padlock 18 is engaged with hole 11, and the enlarged end of the keyhole slot, and to prevent displacement of the padlock, a small chain 19 is fastened at its opposite ends to said padlock and 15 the lower bracket.

When the rod is disengaged from the brackets, a large number of perforated towels (not shown) can be slipped upon it, preferably on the upper arm, and then the 20 rod is secured to the brackets as explained, and the padlock is secured in place for the purpose of preventing any one from readily slipping one of the towels off the rod. After each clean towel suspended from the 25 upper arm is used, it is slipped over the arched or humped portion 12^a and down upon the upright portion and onto the lower arm, where it hangs until removed for washing, it being noted that the arched or 30 humped portion of the rod guards against accidental passage of clean towels from the upper to the lower arm of the rod.

From the above description it will be apparent that I have produced a towel rack 35 possessing the features of advantage enumerated as desirable in the statement of the object of the invention, and I wish it to be understood that I reserve the right to make such changes as fall within the principle of 40 construction defined by the appended claims.

I claim:

1. A towel rack comprising a towel guide and retaining member; detachable connections for the ends of said member, one of 45 said connections consisting of means for engaging and releasing the corresponding end of said member when shifted out of normal position of use, and the other connection consisting of means for engaging and holding 50 the corresponding member end in normal position of use; and means for locking said member end in engagement with said other connection, substantially as described.

2. A towel rack comprising a towel guide 55 rod; detachable connections for the ends of said rod, one of said connections consisting of means for engaging and releasing the corresponding end of said rod when shifted out of normal position of use, and the other 60 connection consisting of means for engaging and holding the corresponding rod end in normal position of use; and means for locking said rod end in engagement with said other connection, substantially as described.

3. A towel rack comprising a combined

towel supporting and guide member; detachable connections for the ends of said member, one of said connections consisting of means for engaging and releasing the corresponding end of said member when shifted 70 out of normal position of use, and the other connection consisting of means for engaging and holding the corresponding member end in normal position of use; and means for locking said member end in engagement with said other connection, substantially as described.

4. A towel rack comprising a combined towel supporting and guide rod; detachable connections for the ends of said rod, one of 80 said connections consisting of means for engaging and releasing the corresponding end of said rod when shifted out of normal position of use, and the other connection consisting of means for engaging and holding 85 the corresponding rod end in normal position of use; and means for locking said rod end in engagement with said other connection, substantially as described.

5. A towel rack comprising upper and 90 lower securing members adapted to be arranged on a support, the upper member consisting of a socket adapted and arranged to receive a rod end when in upwardly inclined position and to interlock therewith when 95 rocked downwardly into substantially horizontal position, and the lower securing member consisting of a socket having an inverted key hole slot therein; a spring rod bent into substantially U form and having 100 its ends detachably engaging said securing members; and a lock arranged to lock the lower end in the lower securing member, substantially as described.

6. A towel rack comprising a rod adapted 105 to be threaded through towels, and embodying a horizontal arm, a vertical arm terminating at its free end below the free end of the horizontal arm, and a hump rising above the horizontal arm and connecting the same 110 and the upper end of the vertical arm, a pair of suitably-supported brackets engaged by the free ends of said arms, and key-controlled means to secure the rod against unauthorized detachment from the said 115 brackets.

7. A towel rack, comprising a pair of brackets, one being hollow and having a keyhole-shaped slot of which the narrow portion is nearest the other bracket, and a 120 U-shaped spring rod arranged with its arms substantially horizontal; one of the arms engaging one of the brackets and the other arm being capable of being fitted into the other bracket through the enlarged end of 125 the keyhole slot thereof, the last-named arm having grooves at opposite sides to receive the edges of the walls of the bracket at opposite sides of the narrow portion of the keyhole slot.

8. A towel rack comprising a pair of brackets, one being hollow and having a keyhole-shaped slot of which the narrow portion is nearest the other bracket, a U-shaped spring rod arranged with its arms substantially horizontal, one of the arms engaging one of the brackets and the other arm being capable of being fitted into the other bracket through the enlarged end of the keyhole slot thereof, the last-named arm having grooves at opposite sides to receive the edges of the walls of the bracket at opposite sides of the narrow portion of the keyhole slot, and a locking device extending through the slotted bracket to prevent the 15 arm engaging the narrow portion of the keyhole slot from being sprung downward into the enlarged portion of said slot.
- In testimony whereof I affix my signature, in the presence of two witnesses.
